HARTVIG SORLEY, OF MACOMB, ILLINOIS.

CARRIAGE STRUCTURE FOR AEROPLANES.

1,269,873.

Specification of Letters Patent. Patented June 18, 1918.

Application filed May 23, 1917. Serial No. 170,485.

To all whom it may concern:

Be it known that I, HARTVIG SORLEY, a subject of the King of Norway, residing at Macomb, in the county of McDonough and State of Illinois, have invented certain new and useful Improvements in Carriage Structures for Aeroplanes, of which the following is a specification.

This invention relates to aeroplanes, and particularly to landing and launching mechanism therefor.

The primary object of the invention is to provide improved running or supporting gear for aeroplanes, which is arranged in such manner as to absorb the shocks and jars incident to the landing of the machine after flight, whereby straining or breaking of the fragile parts of the aeroplane will be wholly obviated.

20 A further object of the invention is to provide improved cushioning mechanism for the running gear of an aeroplane which automatically compensates for the jars or shocks to which running gear frames will be subjected, and includes improved mechanism whereby the degree of resistance of the cushioning element is varied according to the degree of shock transmitted to the running gear frames.

30 Still further objects reside in providing shock absorbing means for the running gear for aeroplanes which is of comparatively simple construction, which is composed of relatively few movable parts, all of which are so constructed and assembled as to minimize the opportunity for wear or breakage, which is wholly automatic in operation, and which will prove highly efficient in practice.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:—

Figure 1 is a side elevation of an aeroplane equipped with running gear constructed in accordance with the invention;

Fig. 2 is a front elevation of the machine; Fig. 3 is an enlarged sectional view taken

through a portion of the aeroplane frame, and illustrating in side elevation the improved wheel frame;

Fig. 4 is an enlarged vertical sectional view taken through the wheel frame;

Fig. 5 is a sectional view taken on line 5-5 of Fig. 4;

Fig. 6 is an enlarged sectional view taken on line 6-6 of Fig. 4; and

Fig. 7 is a sectional view taken substantially upon line 7-7 of Fig. 6.

The improved running gear mechanism herein shown and described is adapted particularly for use in connection with aeroplanes of the type illustrated in my co-pending application, filed July 15th, 1916, Serial Number 109,531, but may be used with equal facility with other types of aircraft.

Depending from the under structure of the aeroplane body are running gear supporting brackets indicated generally at 10, and any preferred number of such brackets may be employed. In the present instance, these running gear supporting brackets are located one at each side of the aeroplane and adjacent to the forward end thereof, and one at the rear or tail end of the aeroplane and preferably midway the sides of the machine, as indicated in Figs. 1 and 2.

Each running gear bracket carries a vertically disposed cylinder 11 within which a piston 12 is mounted for reciprocation. This cylinder is adapted to contain air for cushioning the shocks to which the running gear of the aeroplane is subjected, and the air may be led to the cylinder through suitable pipes from a storage tank indicated at 13.

I have illustrated in the drawings means for supplying the storage tank 13 with compressed air, and this means includes a relatively large worm gear 14 in mesh with a worm 15, driven by the crank shaft of a motor or engine 17 used in propelling the aeroplane. This worm gear rotates a crank shaft 18, to which the driving rods 19 for operating the pumps 20 are connected. The air is forced from the pump cylinders through the pipe 21 into the compressed air storage tank 13.

Arranged adjacent to the cylinder for each running gear frame is a pair of chambers 22 and 23, the former being preferably located directly above the chamber 23. The 5 upper chamber 22 will be referred to as the exhaust chamber, while the lower chamber 23 will be termed the supply chamber. The exhaust chamber is provided in its bottom with an opening or exhaust port 24, which 10 is adapted to be closed by a valve head 25 secured on the upper end of a vertically reciprocable valve rod 26, and the valve head is normally held in seated position over the port or opening 24 by an expansion 15 spring 27. The rod 25 extends into the chamber 23, and carries a head 28, adapted to close a feed or supply opening 29 at the upper end of the chamber when the valve rod is raised. When the valve rod is in such 20 position that the exhaust port 24 in the upper chamber is closed, the head 28 on the lower end of the stem will be removed from the opening 29 so that air may flow therethrough. Air is led to the lower end of the 25 chamber 23 from the storage tank 13 through a pipe 30, and a connecting pipe 31 establishes communication between the upper ends of the chambers 22 and 23. The cylinder 11 is supplied with air passing 30 through a pipe or duct 32 communicating with the upper end of the chamber 22.

From this construction, it is apparent that when the head 25 is in such position that the exhaust port 24 of the upper chamber is closed, air may pass directly from the storage tank, through the lower or supply chamber 23, through the connecting pipe 31 to the upper chamber 22, and thence through the pipe 32 into the upper end of 35 the cylinder 11, whereupon the piston 12 therein will be forced downwardly. When the valve heads are thus positioned, the escape of air from the exhaust chamber will be prevented, but when the valve stem has 40 been moved upwardly so as to unseat the head 25, air may escape from the cylinder through the pipe 32 and port 24. When the valve stem has been raised to air exhausting 45 position, the head 28 will be seated over the opening 29 in the upper end of the lower or supply chamber, whereupon the air supply coming through the pipe 30 will be checked. Upward movement of the piston 12 in the cylinder 11 will then cause the air 50 within the cylinder to exhaust through the port 24.

Mounted for vertical sliding movement in suitable guides 33 are the forks 34 of the running gear frame. Ground engaging 55 wheels 35 are rotatably mounted upon suitable axles carried by the forks at their lower ends, and the upper ends of the forks are connected with the piston by a rod 36. The supporting forks for the ground engaging

wheels are so arranged within the guides 65 33 that when the aeroplane lands, the air craft will have a tendency to settle down upon the ground wheels, whereupon the pistons 12 within the various cylinders will move upwardly unless checked by the air 70 within the cylinders, but just as soon as air is admitted to the cylinders in sufficient quantity to bear the weight of the aeroplane body, the said body will rise upwardly until limited in such movement by the engagement of the pistons with the lower heads of 75 their respective cylinders.

Associated with a running gear mechanism of this character is improved means 80 for varying the degree of air pressure within the cylinders 11, so that the settling movement of the aeroplane body upon the various pistons will be gradual and yet positive, and after the machine has alighted upon the ground and is traveling upon its 85 running gear, such jars or shocks as might be transmitted to the aeroplane body by unevenness of the ground will be absorbed by the cushioning cylinders. This means includes valve rod actuating levers 37, pivoted as at 38 at their inner ends to a suitable bearing 39 affixed to the stationary portion of the running gear frame, or bracket. The outer ends of these levers are connected by a cross member 40, and the outer ends of 90 said levers pivotally support between them the inner end of a finger or latch 41. This finger carries a shoulder 42 which engages with the cross member 40, whereby upward swinging movement of the finger is limited. A spring 43 normally holds the finger 41 in 95 horizontal or outwardly extending position, with its shoulder portion 42 engaged with the cross member 40. The levers 37 extend one upon each side of the valve rod 26, and are connected with the said valve rod by 100 links 44. When the finger 41 is engaged by an upwardly moving element, the levers 37 will be rocked upon their pivots 38 in an upward direction, and the links 44 will deliver upward pull to the valve rod 26. This movement of the valve rod causes the exhaust port 24 in the upper chamber to be uncovered, and the feed opening 29 in the 105 lower chamber to be closed, as has been before described. Immediately upon the finger 41 being released, however, the expansion spring 27 will force the valve heads, 110 rod and rod lifting mechanism back to normal position. Should the finger 41 be engaged by an element moving downwardly, no actuation or movement of the valve rod could take place, as the finger 41 would rock downwardly upon its pivot and against the tension of the spring 43.

Connected to the fork of the running gear mechanism is a rod 45, which is disposed vertically and passes in close proximity to

the valve rod actuating mechanism. This rod slides through bearings 46 carried by the running gear bracket, and the said rod has projecting inwardly therefrom spaced 5 stops 47 and 48 respectively. These stops are adapted when the rod 45 moves upwardly, to engage one at a time with the outwardly projecting finger of the valve actuating mechanism, to vary the degree of 10 air pressure within the cylinder. It will be observed that an appreciable amount of travel between the cylinder and movable running gear frame will be permitted before the uppermost stop 47 engages the finger 41. When such movement takes place, it is obvious that the air within the cylinder will be compressed, and will absorb the shocks to which the wheels on the forks will be subjected. As soon as the aeroplane 15 20 frame settles further, however, the finger 41 will engage the uppermost stop 47, whereupon further downward movement of the aeroplane frame will cause the valve stem or rod 26 to move upwardly, unseating the 25 exhaust valve, and closing the supply valve. This action of the valves enables the compressed air within the cylinder 11 to exhaust, whereupon the vehicle frame may settle further upon the wheel fork. This settling movement, is, however, cushioned immediately so as to prevent breakage or straining of the parts, as the finger 41 passes from engagement with the upper stop 47 and the spring 27 immediately restores the 30 35 valve rod and heads to normal position. Immediately, then, air enters the cylinder 11, to check the inward movement of the piston 12, and this air continues to flow until the vehicle frame and running gear move 40 45 relatively to each other a distance sufficient to enable the finger 41 to engage the lowermost stop 48. This movement will cause the valve rod 26 to again be lifted, whereupon the highly compressed air within the cylinder 11 will again be momentarily relieved. From this construction, it is seen that an air cushion is provided between the ground engaging wheels and the frame of the vehicle 50 and the degree of pressure within the cylinders is varied accordingly as the vehicle frame and ground engaging wheels move toward or away from each other. When the air craft is passing over smooth ground or is stationary, the air will pass from the supply tank into the cylinders, and will cause the air craft to rise and be yieldably supported in raised position. As the body 55 of the air craft moves upwardly as the pressure in the cylinders is increased, the latch 60 or finger 41 will idle over the stops 47-48, and no action of the valve rod will take place.

The foregoing discloses a simple and yet thoroughly efficient means for absorbing the

shocks incident to the landing of the aero- 65 plane, and the various parts are so constructed and assembled that the opportunity for wear or breakage during operation is greatly minimized.

While the present disclosure is that of 70 what is believed to be the preferred embodiment of the invention, it is to be understood that the invention is not limited thereto, but that various changes in the minor details of construction, proportion and arrangement of parts may be made without departing from the spirit of the invention 75 as defined in the appended claims.

What is claimed is:—

1. In an aeroplane, a movable supporting 80 frame, an air cylinder, a piston in said cylinder, a connection between said piston and said frame, an air supply pipe communicating with said cylinder, a pair of valves in said pipe, one of said valves being a relief 85 valve, the said valves being adapted to open and close alternately, a finger for operating said valves, a rod connected to said movable frame, and a pair of stops arranged in spaced relation on said rod and being adapted 90 to engage said finger to operate said valves when said frame moves in one direction.

2. In an aeroplane, a movable supporting 95 frame, an air cylinder, a piston in said cylinder, a connection between said piston and said frame, an air supply pipe communicating with said cylinder, a pair of valves in said pipe, one of said valves being a relief valve, the said valves being adapted to open 100 and close alternately, a finger adapted when moved in one direction to actuate said valves, and a pair of stops carried by said frame and being adapted to operate said finger when said frame moves in one direction. 105

3. In an aeroplane, a body, cylinders depending from said body, a source of fluid supply on said body, pistons in said cylinders, wheel yokes connected to said pistons, 110 a pipe connecting each cylinder with said source of supply, valves in said pipe, and means operable by sliding movement of said piston for operating said valves to sever or make communication between said cylinder 115 and said source of supply.

4. In an aeroplane, a body, a source of air supply on said body, cylinders depending from said body, pistons in said cylinders, wheel forks carried by said pistons, a 120 pipe connecting said air source with each cylinder, valves in each pipe, a rod connecting the valves of each pipe, the said valves being arranged to close alternately upon reciprocation of said rods, one valve in each 125 pipe being an exhaust valve, a finger on each rod, a bar secured to the fork of each piston, a pair of lugs on each bar adapted

to engage one at a time with said fingers, and means for automatically moving said valve to initial position when released by said lugs.

5. In an aeroplane, a movable supporting frame, an air cylinder, a piston in said cylinder, a connection between said piston and said frame, an air supply pipe communicating with said cylinder, a relief valve in said 10 pipe, a check valve in said pipe, a connection between said valves whereby one will be open when the other is closed, a finger

for operating said valves, means for normally holding said relief valve open, and a stop on said frame adapted to engage said finger when the frame is moved in one direction to reverse the position of said valves.

In testimony whereof I affix my signature in presence of two witnesses.

HARTVIG SORLEY.
